UNITED STATES PATENT OFFICE.

CHARLES R. MCADAMS, OF EVANSVILLE, INDIANA, ASSIGNOR TO KIECHLE, BRENTANO & OBERDORFER, OF SAME PLACE.

DESIGN FOR A STOVE-DOOR.

SPECIFICATION forming part of Design No. 21,514, dated May 3, 1892.

Application filed April 5, 1892. Serial No. 427,942. Term of patent 7 years.

To all whom it may concern:

Be it known that I, CHARLES R. MCADAMS, of Evansville, in the county of Vanderburg and State of Indiana, have invented and produced a new and original Design for Stove-Doors, of which the following is a specification.

This design consists in the ornamentation of the stove-door, and is illustrated in the accompanying drawing, wherein the design is shown applied to the oven-door of a cooking stove or range. At the lower right-hand corner the door is ornamented by a fan-shaped ornament A, which is characterized by radial rays a, a quadrantal segment b, constituting a name-plate, and radial projections c, simulating feathers. In the center of the fan ornament A is an annular part B. The hinges of the door are ornamented by scroll ornaments C C. The left-hand portion of the door is ornamented by a central rosette D, scroll ornaments E E E, and a foliated ornament F. The upper left-hand corner of the door is ornamented by a scroll ornament G. The upper right-hand corner of the door is ornamented by a scroll ornament H. 25

I claim—

The design for the ornamentation of a stove-door, as shown and described.

CHARLES R. MCADAMS.
